UNITED STATES PATENT OFFICE.

GEORGE O. GRIDLEY, OF WINDSOR, VERMONT.

MACHINE FOR TURNING ECCENTRIC RINGS

No. 893,239.

Specification of Letters Patent.

Patented July 14, 1908.

Application filed November 24, 1905. Serial No. 288,845.

To all whom it may concern:

Be it known that I, GEORGE O. GRIDLEY, of Windsor, in the county of Windsor and State of Vermont, have invented certain new and useful Improvements in Machines for Turning Eccentric Rings, of which the following is a specification.

This invention relates to metal working machines, and more particularly to those applicable to the production of eccentric rings, such as used for packing pistons, and the like.

It has for its principal object the provision of an efficient machine whereby the rings may be automatically bored, turned eccentrically, and cut off from a suitable blank.

In the accompanying drawings, in which similar characters designate like parts throughout the several views,—Figure 1 is a front elevation of one embodiment of my invention. Fig. 2 is an enlarged broken end elevation thereof looking from the right in Fig. 1, and Fig. 3 is an enlarged broken top plan view. Fig. 4 represents a section on the line 4—4 of Fig. 2.

The numeral 10 designates a supporting frame, in which is journaled a work-spindle 11 rotatable at the desired speed by fast and loose pulleys 12 mounted upon a driving-shaft which is connected to the work-spindle by gearing inclosed in a case 13. Fixed to the spindle is a face-plate 14, upon which may be bolted a blank or hollow cylinder B from which the rings are to be formed. Mounted to slide in ways 15 at one end of the frame is a tool support 16 which may be reciprocated longitudinally of the work-spindle by a feed bar 17 extending through the frame to the opposite end. Here it has a contact projection 18 preferably provided with a roll 19 co-operating with a cam-face 20 upon the periphery of a cylinder 21. The cylinder is fast upon an actuating shaft 22 mounted to rotate in the lower portion of the frame, and geared to the driving shaft or being operated in any other convenient manner.

Fixed to the support 16 is a post or tool-holder 23 adapted to receive a boring bar 24, the axis of which is situated in alinement with that of the work-spindle and which carries at its inner extremity a tool 25, the cutting edge of which operates over a surface concentric with the spindle axis. Projecting from the rear of the support is a block 26 having ways 27 formed in its upper face,

these ways guiding a tool-holder 28 having a recess to receive a turning tool 29 which may be secured in position by set screws 29^a. Depending from the holder through an opening in the block 26 are separated lugs or projections 30, having adjacent parallel faces between which is guided a slide 31. In the slide is a bore to receive an eccentric 32 splined upon an actuating shaft 33 journaled in the block 26 and in the frame. This actuating shaft is rotated at the same speed as the spindle by a spur-gear 34 meshing with a similar gear 35 of the same pitch diameter and having the same number of teeth, this latter gear being secured upon the spindle adjacent to the face-plate.

From the front of the frame near the face-plate projects an arm 36 upon which is mounted to slide a block 37 carrying a tool support 38. The tool support may be adjustably mounted upon the block by means of bolts 39 extending into the undercut slots 40 in said block. This arrangement permits a variation in the position of the support 38 longitudinally of the spindle axis. A portion 40^a of the support 38 which serves as a holder is shown as inclined at an angle to the spindle axis, it diverging therefrom as it approaches the face-plate. Across the upper side of the holder, lying substantially at right angles to the spindle, are slots 41 in which are located cut-off tools 42, there being such a number of these as will divide the block into the desired number of rings. The tools are shown as 90 clamped in the slots by plates 43 bearing upon their upper edges and retained in place by screws 44 threaded into the holder. The cutting edges of the tools are preferably situated at successively greater distances from 95 the spindle or lie in a line inclined similarly to the adjacent edge of the holder. They may be adjusted with respect to their projection beyond the holder by screws 45 threaded through a vertical wall 46 at the 100 outer side of the holder and contacting at their inner ends with the extremities of the tools. As illustrated, the support 37 is reciprocated laterally of the spindle by a lever 47 fulcrumed upon the end of the frame at 48. From the lower end of the lever is a projection 49 co-acting with a cam-face upon a disk 50 fast upon the end of the actuating shaft 22 opposite the cylinder 21.

In using my improved machine the hollow 110 cylinder or blank B is bolted to the face-plate with its axis coinciding with that of the

work-spindle. The machine being in motion, the boring bar and the turning tool, since they are mounted upon a common support, advance simultaneously to bore out the interior of the blank concentrically with the spindle axis and to turn off its exterior eccentrically, this latter operation being effected by the reciprocation of the holder 28 which is moved by its eccentric sufficiently to give a minimum chip at one side of the blank and a maximum at the opposite side, the difference between the two being in proportion to the eccentricity desired. As the boring bar and turning tool move along the work the cutting-off tools are automatically advanced, the first of the series beginning its cut just at the rear of the boring bar and nearly completing its operation before the second of the series comes into action, in this way decreasing the resistance to feed. As the eccentricity of the cylinder as turned is wholly upon the outside, with the bored interior concentric to the spindle axis, each of the tools 42 completes a cut over the entire inner surface of the cylinder at substantially the same instant, so that the ring is left wholly free to fall from the blank and is supported by the bar. If the eccentricity were attained by boring out the blank off center, the ring 30 would be severed first at one side and by its retention by the thinned portion would tend to swing to one side, causing the remainder of the cut to be made out of true and possibly causing breakage of the tool. The cutting 35 off thus continues until the last of the series of tools has passed through the turned blank, when the operation upon that particular blank is completed and the rings may be removed from the bar and a new blank applied 40 to the face-plate.

It will be seen that this machine acts automatically throughout the operation upon each blank, and that the rings are produced rapidly and accurately without undue strain upon the tools or their supports.

45

Having thus explained the nature of the invention, and described a way of constructing and using the same, although without attempting to set forth all of the forms in which it may be made, or all of the modes 50 of its use, I declare that what I claim is:

1. A machine of the character described comprising a work spindle, a boring tool arranged concentrically with the spindle, a turning tool, means for reciprocating the 55 turning tool to produce an eccentric surface on the work, a plurality of cutting-off tools arranged to successively engage the work in the rear of the turning tool as the turning tool moves along the work, and means for simultaneously feeding said turning tool, said boring tool, and said cutting off tools.

2. A machine of the character described, comprising a work spindle, a tool slide, a boring tool on said slide arranged concentrically 65 with the spindle, a turning tool on said slide, means for reciprocating said turning tool to produce an eccentric surface on the work, a plurality of spaced cutting-off tools arranged with their cutting edges in a line inclined to 70 the axis of the spindle, a second slide for supporting the cutting-off tools, and means for simultaneously actuating said slides substantially as set forth.

In testimony whereof I have affixed my 75 signature, in presence of two witnesses.

GEORGE O. GRIDLEY.
